Attorney,

UNITED STATES PATENT OFFICE

WILLIAM J. GRAY, OF EUGENE, OREGON

CHANGEABLE EXHIBITOR

Application filed January 3, 1929. Serial No. 330,095.

My present invention relates to improvements in changeable exhibitors of the manually operated, rotatable type, employing a web having its ends attached to rollers so as to be wound upon one roller as it is unwound from the other, for successively displaying the signs, characters, advertising matter, or other subjects matter displayed on the web. One of the rollers is an automatically operating, spring wound roller which assists in maintaining the web stretched taut between the winding and the unwinding roller, and also re-winds the web when permitted to do so, to reverse the movement of the web as required. The operating roller is positively and intermittently rotated to wind the web thereupon against the tension of the spring controlled or spring wound roller, and a take up device that is longitudinally movable with relation to the operating roller is provided for the operating means to provide for the intermittent movement of the operating roller in both forward and reverse direction.

While the device of my invention is adapted for the display of various kinds of changeable exhibitors, it is particularly designed for changing the street signs carried by street railway cars, busses, &c. and the exhibitor is operated by either the conductor or the motorman of the vehicle, as conditions require.

The invention consists in certain novel combinations and arrangements of parts as will hereinafter be more fully set forth and claimed.

In the accompanying drawings I have illustrated one complete example of the physical embodiment of my invention wherein the parts are combined and arranged according to the best mode I have thus far devised for the practical application of the principles of my invention.

Figure 1 is a face view showing the

changeable exhibitor installed on a street railway car or bus, and in position for use.

Figure 2 is an end view of the device showing also parts in section representing the front and rear walls of the vehicle, with the operating cord extending to the rear end of the vehicle.

Figure 3 is a sectional view of the case, at line 3—3 of Figure 2 showing the web and operating parts therefor.

Figure 4 is an enlarged transverse vertical sectional view at line 4—4 of Figure 1.

Figure 5 is an enlarged view at the operating end of the operating roller, with parts in section.

Figure 6 is a perspective view showing part of the operating means for the operating roller.

In carrying out my invention I utilize a pair of parallel rollers as the spring controlled roller 1 and the operating roller 2 that are enclosed in the case or cabinet 3 and located at a suitable place in the vehicle for observation by the passengers, as on the front wall 4. An operating cord 5 may be pulled by the motorman or driver of a vehicle having a one-man crew, or with vehicles having a two-man crew the cord passes to the rear of the vehicle, over guide pulleys as 6 to a suitable location for access by the conductor.

A window 7 is provided in the face of the cabinet so that the signs street designations, or other subject matter, may successively be displayed from the web 8 which has its ends attached to the respective rollers 1 and 2.

The spring controlled roller 1 is of the type used for automatic window shades rollers, and this roller is provided with a spring indicated as 9 for use with the shaft 10 that is journaled, as at 11, in the opposite ends of the case or cabinet and squared at one end so that it may be held immovable and form an abutment for the spring 9.

The operating roller 2 is provided with a shaft 12 that is journaled in bearings 13 in

the opposite ends of the case 3, and this roller is manually operated, at intervals, to wind the web thereupon from the spring controlled roller in one direction, and then to release 5 the web and permit it to be re-wound upon the spring controlled roller, at intervals, as the car travels in the reverse direction over its route.

The operating roller is retained under tension 10 as to its rotary movement so that the web may be stretched taut, with the assistance of the spring controlled roller, at all times, by means of a friction or tension device comprising a friction block 14, which may be of wood and bears against the shaft of the roller. The friction block is enclosed in a pocket at 15 one end of the case, and a spring 15 holds the block in frictional contact with the shaft, an adjusting bolt or screw 16 being used to 20 adjust the tension on the shaft. The pocket is closed by an end plate 17 which may be removed as desired to give access to the friction parts.

The block 14 is a friction block in two halves 25 or sections, the upper section being spring pressed to maintain an even pressure or tension on the shaft of the roller 2. This tension is sufficient to prevent the spring roller from winding the web back upon itself, when the 30 pawls are reversed to the positions shown in dotted lines in Figure 6, the spring 29 acting on the lower end of the lever 21 will force the roller in the reverse position when the pawl 28 engages any one of the set of lugs 19.

At one end of the operating roller I provide 35 three series of teeth or ratchets 18, 19 and 20, that are spaced longitudinally of the roller and arranged approximately 120 degrees apart around the circumference or outer periphery of the roller. The teeth of each 40 series are stepped back or circumferentially as well as longitudinally, so that by pulling the cord 5 three times the operating means, as a lever 21, is actuated to turn the roller through one complete revolution, and display 45 three distinct signs on the web at the window 7.

The signs are displayed, of course in succession, and the number of pulls to a revolution 50 of the operating roller will depend upon the number of streets to be successively displayed, the size of the rollers, the arrangement of the series and the number of the series of ratchet teeth &c.

The operating lever 21 is supported in 55 pivotal manner by means of a hub 22 which is threaded on the threaded portion 23 of the operating shaft 12, and this hub is movable not only through an arc about the shaft, but 60 also longitudinally of the shaft under action of the screw threads, the rotation of the shaft, and the oscillation of the lever 21, as the latter is pulled by the motorman.

On the lever 21 is a laterally projecting lever 65 arm 24 having a rounded surface adjacent

the roller, and this lever arm carries two oppositely arranged pawls 25 and 28, each pivoted as at 26 on the perpendicular faces of the lever arm, and adapted to be swung on their pivots into operative or inoperative position as indicated by dotted and full lines for the pawl 28 and by full lines and dotted lines for the pawl 25. The pawls are of resilient material, and when turned to operative position, a pawl is located between a pair of guide lugs 70 27 spaced apart on the lever arm, and in position to co-act with the ratchet teeth on the roller. Pawl 25, for instance, may be used for turning the roller on the "out" trip of a street car, and then pawl 28 is used for the "in" trip of the car, the pawls being "snapped" 75 into and out of operative position with relation to the ratchet teeth.

The pawls are of spring metal, and when a pull is exerted on the cable or cord 5, the pawl 28 will skip over the lugs 19; then when the cord is released, the pawl 28 will engage a lug 19 and the springs 29 will overcome the spring 80 pressed friction block 14, and turn the roller 2 backwards. At the same time the spring 90 roller 1 will be allowed to turn and wind the web upon itself.

A spring 29 is attached at one end to the operating lever and at its other end is anchored to a part of the casing 3 to return the 95 lever to operative position after it has been pulled, and to hold the lever in normal position for engagement with the ratchet teeth as indicated in Figure 4.

In Figure 4 it will be apparent that the 100 pawl 25, by contact with the ratchet 18, when the cord 5 is pulled to swing the lever 21, will turn the operating roller to wind the web thereupon and unwind the web from the spring controlled roller for the display of another sign, and this operating is repeated 105 until the end of the route is reached. At the end of the route the pawl 25 is turned to dotted position in Figure 6 and pawl 28 is also turned to dotted position, the former being 110 inoperative and the latter now operative for contact with the ratchet teeth.

With pawl 28 in contact with a ratchet, a pull on the cord releases the pawl from the ratchet and permits the spring controlled 115 roller to wind the web thereupon for the display of a new sign, and the turning movement of the operating roller is terminated when the ratchet encounters the advanced pawl.

Each turn of the hub on the threaded shaft 120 together with the turn of the shaft, moves the hub and pawl longitudinally of the roller, and the pawl is thus adapted to engage a successively stepped tooth of the ratchet or series of teeth, and thus impart the turning 125 movement to the operating roller.

The winding of the web from the top roller 3 to the bottom roller 2 increases the size of the latter and a complete revolution of the larger roller will display more of the sign 130.

than would be the case when the major portion of the web is on roller 1. To compensate for this condition, the spaced lugs are used in order that after one revolution of the roller 2, the boss 22 carrying the pawl mechanism will be shifted toward the roller 2 on the screw threads 23, and at the beginning of the second revolution the pawl 25 engages a second lug 18 on the roller 2. In Figure 6 it will be seen that the lever 21 attached to the boss 22 and its arm 24 that carries the pawl 25 turns through a short arc before engaging the lug 18, which cuts down or limits the travel of the roller 2 when the lever 21 has passed through one movement due to the pull of the cord 5.

It will be understood that as the roller 2 revolves the lever 21 is pulled forward and then the roller remains stationary while the spring 29 pulls the lever 21 back to engage another lug with the pawl 25. This single pull on the lever rotates the roller one third of a revolution, and when the lever 21 is released it moves back to position, in Figure 4 to engage another succeeding lug with pawl 25. The friction block 14 holds the roller 2 stationary against action of the spring roller 1 while the lever 21 moves back.

In rotating the roller 2 forward to wind the web upon itself, the pawl 25 is employed while the pawl 28 remains idle. When it is desired to reverse the movement and wind the web on roller 1 the pawl 25 is moved to position dotted lines in Figure 6, and pawl 28 is also moved to dotted line position so that the latter pawl may engage the lugs to reverse the roller.

It is apparent from the foregoing description that while the roll 2 is rotating forward the pawl 28 is idle and when the motion is reversed the pawl 25 is idle. These pawls are resilient and they slide up and over the lugs when going back to engage a succeeding lug similar to a ratchet movement.

Having thus fully described my invention, what I claim as new and desire to secure by Letters Patent is:—

1. The combination with a spring controlled roller, an operating roller having stepped ratchets thereon, a shaft for the operating roller and a web connected to said rollers, of an operating lever pivoted on the shaft, reversible pawls carried by said lever for alternate co-action with said ratchets, and a spring for holding the lever in normal position.

2. The combination with a spring controlled roller, an operating roller having stepped ratchets thereon, a shaft for the operating roller, and a web connected to said rollers, of means for applying frictional tension on said shaft, a spring retained lever and a lever arm thereon, and a pair of reversible pawls carried by said ram for alternate co-action with the ratchets.

3. The combination in a changeable exhibitor as described with an operating roller and its shaft, of a lever pivoted on the shaft and co-acting means on the shaft and lever for causing longitudinal movement of the lever on the shaft, ratchets on the operating roller, a pawl carried by the lever for co-action with the ratchets, and a spring for holding the lever in normal position.

In testimony whereof I affix my signature.

WILLIAM J. GRAY.
